SHOT GUN SHELL BOX

William R. Sauey, Baraboo, Wis., assignor to Flambeau
Plastics Corp., Baraboo, Wis.

Application September 8, 1958, Serial No. 52,555

Term of patent 14 years

(Cl. D58—13)

The sides not shown are the same as the sides shown.

I claim:

The ornamental design for a shot gun shell box, substantially as shown and described.
